UNITED STATES PATENT OFFICE.

JOHN A. KOLLER, OF MANHATTAN, KANSAS.

BUNDLING-MACHINE.

1,079,864.

Specification of Letters Patent. Patented Nov. 25, 1913.

Application filed February 10, 1913. Serial No. 747,493.

To all whom it may concern:

Be it known that I, JOHN A. KOLLER, a citizen of the United States, residing at Manhattan, in the county of Riley and State of Kansas, have invented certain new and useful Improvements in Bundling-Machines, of which the following is a specification, reference being had to the accompanying drawings.

10 This invention relates to new and useful improvements in bundling machines such as are adapted to be employed for holding wall paper rolls, laths and similar loose members in a compact bundle, while wrapping the 15 same with a binding medium such as wire or cord.

The object of the invention is to provide a bundling machine which may be quickly and easily operated, which comprises few 20 and durable parts and which will hold wall paper rolls or similar members in a very tight and compact bundle.

Another object of the invention is to provide a bundling machine of the above character which will possess advantages in points 25 of efficiency and durability, is inexpensive of manufacture and at the same time is simple in construction and operation.

With the above and other objects in view, 30 the invention consists in the novel features of construction and the combination and arrangement of parts hereinafter more fully described, pointed out in the claims and shown in the accompanying drawings, in 35 which—

Figure 1 is a side elevation of a bundling machine constructed in accordance with my invention. Fig. 2 is a sectional view taken on the line 2—2 of Fig. 1. Fig. 3 is a detail fragmentary vertical sectional view and Fig. 4 is a vertical detail sectional view.

Referring more particularly to the drawings, 1 indicates the spaced upright standards which are suitably connected at their 45 upper ends by means of the longitudinal rod 2. Pivotaly mounted upon the rod 2 adjacent each end thereof are the curved arms 3 and 4, each set of arms being arranged in opposed relation and the inner ends thereof 50 coiled upon the rod, as shown at 5, and the extreme ends disposed in a horizontal plane, as shown at 6, and pivotaly secured to the upper ends of the links 7, the lower ends of 55 said links being pivotaly mounted upon the longitudinal rod 8, the ends of which are

slidably mounted in the vertical grooves 9 formed in the standards 1.

Mounted upon the rod 8 and suspended therefrom are the vertical supporting members 10, in the lower ends of which is pivotally mounted the longitudinal connecting bar 11. The connecting bar 11 is secured to the upper face of the foot treadle 12, the inner end of said treadle being hingedly secured to one of the longitudinal rods 13 which connect the lower ends of the standards 1. Mounted upon one of the rods 13 opposite the hinged end of the treadle 12 and extending upwardly at an angle therefrom is a supporting member 14, the upper 60 end of which is suitably mounted upon the rod 2. The supporting member 14 is disposed through the longitudinal opening 15 in the treadle 12 and mounted thereon is a plate 16, one of the longitudinal edges of 65 which is provided with the teeth 17 which are adapted to be engaged by the catch member 18 carried by the treadle to hold the treadle in various positions.

From the above description, it will be apparent that by downward pressure upon the outer end of the foot treadle, the arms will be brought together and closed upon a bundle of wall paper rolls or other members to 80 securely hold them in position while being tied. Upon releasing the foot treadle 12, the coil springs 19, the ends of which are secured to the rods 2 and 8 respectively, will 85 return the arms to their normal position.

In the practical operation of my device, 90 the arms 3 and 4 are normally disposed in the position shown in Fig. 2. The rolls of wall paper or other similar articles are placed between the arms and the foot treadle 12 is then pressed downwardly until the 95 rolls are pressed into compact form, the catch member 18 engaging beneath the end of the teeth 17 to hold the treadle and arms in position while the bundle is being tied. After the bundle has been tied, the foot 100 treadle is released and the springs 19 which have been placed under tension by the operation, will return the arms to a normal position.

From the above description taken in connection with the accompanying drawings, it will be readily apparent that I have provided a simple and durable bundling machine whereby small rolls, such as wall paper rolls, laths, etc., may be quickly and 110

easily bundled into compact form. It will also be apparent that the device is extremely simple in construction and can be manufactured at a comparatively low cost.

5 While I have shown and described the preferred form of my invention, it will be obvious that various changes in the details of construction and in the proportions may be resorted to for successfully carrying my 10 invention into practice without sacrificing any of the novel features or departing from the scope of the appended claims.

What I claim is:—

- 15 1. In a device of the character described, the combination of spaced standards, rods connecting the lower ends of said standards, a longitudinal rod having its ends mounted in the upper ends of said standards, curved arms having their outer ends normally disposed in spaced relation, a foot treadle, means for connecting said treadle to the other ends of said arms for actuating the same, a brace member connecting the first and one of the second rods, and having a 20 plurality of teeth in one of its longitudinal edges, said foot treadle having a longitudinal opening therein in which the brace member is disposed, a catch member carried by the treadle and adapted to removably engage the teeth on the brace member to hold the treadle in various adjusted positions and means for returning said arms to their normal position when the foot treadle is released.
- 25 2. In a device of the character described, the combination of spaced standards, rods connecting the lower ends of said standards, a longitudinal rod having its ends mounted in the upper ends of said standards, curved 30 arms arranged in opposed relation and having their outer ends normally retained in spaced relation, the other ends of said arms being normally disposed in a horizontal

plane, link members pivotally connected to the horizontal portions of said arms, said standards being provided with grooves upon the inner faces thereof, a longitudinal rod having its ends movably mounted within said grooves, said links having their lower ends pivotally mounted upon said rod, a 45 brace member secured to one of the first rods and having a plurality of teeth upon one of its longitudinal edges, a pivotally mounted foot treadle pivotally connected to the last mentioned rod and provided with a 50 longitudinal opening to receive the brace member, a catch member carried by the treadle and adapted to engage the teeth and the brace member to retain the treadle in various adjusted positions, and means for 55 returning the arms to their normal position upon the release of the treadle.

3. In a device of the character described, the combination of spaced standards having grooves formed upon the inner faces thereof, a longitudinal rod connecting the upper ends of said standards, curved arms pivotally mounted upon said rod and having their outer ends normally arranged in spaced relation, link members pivotally secured to 60 the other ends of said arms, a second longitudinal rod having its ends slidably mounted within said grooves, said links having their other ends pivotally mounted upon said rod, means for reciprocating said rod 65 to actuate the arms and force the same toward each other, and coil springs arranged between said rods and having their ends secured thereto to return the arms to their 70 normal position.

In testimony whereof I hereunto affix my signature in the presence of two witnesses.

JOHN A. KOLLER.
